ADOLF FRITZ SCHAUSS, OF OBERURSEL, NEAR FRANKFORT-ON-THE-MAIN,
GERMANY.

TYPEWRITING MACHINE.

Application filed November 21, 1925, Serial No. 70,490, and in Germany December 6, 1924.

This invention relates to a typewriting machine which as regards its outside dimensions corresponds to the known small travelling or portable typewriters but as regards its working corresponds to a complete typewriter. The object of the present invention is thus to construct a small portable typewriter which, whilst retaining the simple carriage return and the advantages of the known office type of machine, has a complete keyboard and is very strong and stable in design without departing from the usual dimensions of the known travelling machines.

The known forms of portable typewriters differ considerably in construction and in arrangement of the keys and type bar mechanism from the larger sized standard office machines and the type bars could not, for example, be arranged in a vertical bank in front of the roller. In consequence the type bars have been arranged to strike downwards on the roller and the radius levers carrying the type move through an angle greater than 90°. In another form of portable machine, the type bars may occupy one or other of two normal positions for the purpose of reducing the height—one position was occupied when the machine was being transported and the other, higher, position when the machine was in use, whereby the angle of swing of the radius levers carrying the type was reduced when the machine was in use. The large type bar swing of these known forms, in addition to other disadvantages, affects the key touch and the complicated and necessary sensitive setting mechanism increase the prime cost of the machine as well as reduce its stability and durability.

According to the present invention the keyboard is of the normal size, having 44 keys in the form herein described, and the height and overall sizes are similar to those of the portable type of machine. These results are attained by the peculiar arrangement of the key and type bar mechanism and the suitable method of guiding the carriage with the paper roller.

In order to enable the roller to be brought as near as possible to the keyboard, without raising the carriage guide, the type bar bracket is arranged vertically in front of the roller and the radius lever carrying the type is so arranged and operated that it only trav-

els through an angle of about 90° from its position of rest into its printing position. 55 All setting mechanism is dispensed with and the operation is simplified. The weight of the machine according to the present invention is thus reduced as compared with other portable machines.

It will be readily understood that such a material increase in the number of keys, under the conditions herein mentioned, renders it necessary to provide a novel type of operating lever mechanism.

It is known in typewriters to transmit the movement of the key lever to the type bar through an intermediate lever. It is also known to make the key lever in several parts and to cause the key push rod to act on the type bar draw bar by means of a link and through an intermediate lever. It is further known to transmit the movement of the key against the action of a spring through a bell crank lever engaging a draw bar and so to the intermediate lever of the type operating mechanism.

Owing to the curtailment of the space left for the key mechanism, the large number of keys reduces the distance between the separate key levers to such an extent that considerable difficulty arises in connection with the arrangement and support of the key levers. According to this invention this difficulty is overcome by interposing a connecting piece between the draw bar of the key lever and the intermediate lever used in the known manner for transmitting the movement to the draw bar of the type bar. In addition all the draw bars from the front row of keys are so formed as to allow the intermediate levers corresponding to the rear row of keys to swing freely.

Other features and improvements will be understood from the following specification and the claims.

One form of the invention is illustrated by way of example in the accompanying drawings, in which:

Fig. 1 is a sectional elevation showing the carriage feed, whilst the machine frame and the parts not appertaining to the type operating mechanism are only indicated diagrammatically.

Fig. 2 is a plan.

Fig. 3 is an end elevation of the machine.

Fig. 4 is a diagrammatic plan view of the type operating mechanism.

Fig. 5 is a detail plan showing the arrangement of the stepped bridge pieces with the key push rod and the key lever pivot.

Fig. 6 is a diagrammatic side elevation of the type operating mechanism.

Fig. 7 is a side elevation to an enlarged scale, showing the transmission mechanism 10 from the key to the intermediate lever.

Fig. 8 is an end elevation of the mechanism of Fig. 7.

Fig. 9 is a plan of the key lever pivot.

Fig. 10 is a plan of part of the space key.

15 Fig. 11 is a detail view of the key push rods used.

Fig. 12 is an elevation showing on the left hand the type bar sector and on the right hand a front elevation of the type bar carrier.

20 Fig. 13 is a plan view of a development of the right hand side of Figure 12.

The frame, made up of sheet steel or duralumin, or the like, is composed of side walls a^1 and a^2 , which are connected by a rear wall a^3 as can be seen in Fig. 2. At its front end the open frame so formed is strengthened and held together by the angle bar a^4 for the key bridge pieces and the parallel arranged transverse bar a^5 which is arranged above the 30 level of the front bar a^4 . Both these bars, as can be seen from Figs. 2 and 5, are interconnected by eleven off-set and step-formed bridge pieces for the key lever pivots. The transverse stiffeners a^3 and a^4 are bolted to the 35 side walls a^1 and a^2 .

In addition to the above mentioned transverse stiffeners, the side walls are joined at their lower edge by a broad web piece a^6 and a stiffener a^7 , which carries the type bar sector, connecting the inwardly flanged upper edges of the side walls. At the front of the machine the side walls are stepped upwards to the inwardly flanged portion and these steps have each an inwardly turned lug for 45 supporting the key guide plates a^{10} .

The stiffener a^7 is stamped out of a flat plate and has broad bearing flanges a^8 , see Figs. 2 and 3, and a turned down segmental portion a^9 to which the type section proper is 50 fixed. The flanges a^8 are at an obtuse angle to one another.

As mentioned above the side walls are stepped, see Fig. 1, corresponding to the number of rows of keys. Each step is covered by 55 a guard and guide plate, which together form a closed in key board which may conveniently be formed of separate angle bars a^{10} . The push rods b pass through slots in these guide plates a^{10} and these push rods are tapered 60 upwards with a reducing taper so that when depressed the push rods b pass freely through the slots, but when the keys are in their normal raised positions, they are held without rattling when the machine is subjected to vibration as in transport. The slits formed in 65

the guard plate are conveniently formed by turning down the sides so as to prevent excessive wear in use.

The keys operate the bell crank levers c through their push rods b which are connected by a pin joint to the said levers. As already mentioned the bell crank levers c are supported in the novel shaped bridge pieces which have off-set steps and are arranged in a front and rear direction and at regular intervals to connect the front transverse bar a^4 to the parallel transverse bar a^5 (Fig. 5). 75

In the form shown eleven stepped bridges d each having four steps, are provided and are arranged so as to support four rows of bell 80 crank levers c . The bell crank key levers c have their substantially horizontal and rearwardly extending arm engaged by the push rod of the corresponding key and the downwardly projecting arm, which is shorter, 85 joined to the draw bars e , (Fig. 7).

The pin joint of the push rod b to the substantially horizontal arm of the key lever c is effected by a pin c^1 fixed in the lever arm over which the push rod is passed loosely. 90 A flat spring c^2 fixed to the side of the lever c also passes over the end of the pin c^1 after the push rod b is in place and locks the said push rod in position (Fig. 9). Owing to the spring action of the part c^2 which embraces 95 the pin c^1 , the push rod cannot cause rattling.

The movement of the downwardly projecting arm of the key lever c is transmitted by a draw rod e to an intermediate lever f to which there is also fixed at its outer free end a second draw rod e^1 extending rearwardly to connect with the type bar g . A direct connection from the key levers c to the intermediate levers f would partially obstruct the depression of the push rods b . As the push rods b of the rear row are placed as near 105 as possible to the type bars so as to reduce the front to back length of the machine, and also as the intermediate lever f is pivoted at its lower end at approximately the same height 110 as the pin joint of the depending arm of the key lever c so as to keep the height of the machine within the desired limits, it is clear that a straight and direct connection from the depending arm of the key lever c to an intermediate point of the interposed lever f would foul the end c^1 of the key lever when the latter was depressed. 115

It is not adequate to give a side off-set to the type lever or the draw bar e in order to 120 ensure the free depression of the pusher rod b and key lever c , owing to the smallness of the space between the draw bars. Any increase in this space to be effective would involve a material increase in the width of the keyboard and also the spreading apart of the intermediate levers f which are mounted side by side on a common transverse shaft. An increase in the size of the keyboard would be a serious disadvantage as compared with 125 130

other portable typewriters. The spreading of the intermediate levers *f* would necessitate such a sharp inclination of the outside draw bars between the intermediate levers *f* and the type bars *g* that these keys would require a very much heavier touch to operate them.

According to this invention by interposing an upwardly and rearwardly bent connector *h* between the draw bar *e* and the intermediate lever *f*, the draw bars can be arranged low in the machine as also the pivot of the intermediate levers *f* and the overall height of the machine is thus retained substantially within the limits necessary for depression of the keys of the rear row together with the operation of their key levers *c* located beneath the keyboard. The connector *h* engages the intermediate lever *f* at a point midway between the low set pivot *f*¹ and the free end. The lower end of the connector *h* is rolled with a side off-set to form an eye which is threaded on to the end of the draw bar *e*.

The intermediate levers *f* are mounted on a common transverse shaft *f*¹ and can be spaced from one another by side extensions on their bosses or by distance washers so that neighboring levers can move freely without affecting one another.

Owing to the large number of keys, the pitch of the intermediate levers *f* is kept as small as possible. The keys in each row are off-set in relation to one another by the amount of this pitch of the intermediate levers. In consequence of this arrangement, the draw bar *e* of the front row key, if straight, will pass the pin joint *c*¹ of the rear row key at a distance in plan equal to the pitch of the intermediate levers *f*, which is inadequate to ensure that the rear row keys on depression will not foul or be obstructed by the draw bar from the front row key (see Fig. 4). The draw bars *e* from the front row keys are therefore bellied as shown where they pass the rear row keys for a sufficient amount to allow the free working of the rear row keys and key levers. It is to be noticed in this connection that the depending arm of the key lever moves from rear towards the front of the machine and transmits a similar movement to the intermediate lever *f*, and connector *h*.

The draw bars *e*, as can be seen from Fig. 8 are bent at their front ends upwardly and then horizontally as at *e*² and *e*³, so that on assembling this machine, the draw bars can be readily hooked into their proper bell crank key levers *c* which are previously set in position on their bridge pieces *d*. The shape of the hook end *e*³ is such that it is impossible for the draw bar *e* to slip out of the eye on the end of the lever *c*. The adjustability of the eyes of the connectors *h* on the draw bars *e* enables accurate and easy setting of the keys of the same row at the same height.

As can be seen from Fig. 8, the connectors *h* with their rolled over eyes, the draw bars *e* with their hook shaped ends and the levers *c* move in different but adjacent planes but the push rod *b* is in the same plane as the draw bar *e*. The bellied portion of the draw bar from the front row key gives ample working clearance to the rear row push bar. On depressing a key in the rear row, the corresponding intermediate lever *f* swings from rear to front. Owing to the off-set eye on the intermediate lever, this swinging can take place without obstruction from the depressed key lever.

The double armed bar *g* carrying the type is pivoted in a pivot *g*¹ carried by a sector *i*. A connector *h* couples the draw bar *e*¹ to the short arm of the type bar. A threaded connecting eye or boss is provided on the connector to engage a thread on the end of the draw bar *e*¹. It will be recognized that by depressing a key, (Fig. 1) the type lever *c* swings counter clockwise, the draw bar *e* and connector *h* swing the intermediate lever *f* clockwise about the axis *f*¹, and the draw bar *e*¹ swings the type bar *g* counter-clockwise as shown by the arrow, from the position shown in full to that shown in dotted lines. The parts are all returned by the springs *l* which are anchored to the hooks *l*² on the cross stiffener *a*⁶ and are also connected to the hooks *l*¹ on the intermediate levers *f*. For this purpose the stiffener *a*⁶ is stamped out with hooks along its entire length as shown in Fig. 2. With this arrangement it will be seen that the springs can be readily inserted, inspected and when damaged renewed.

The transverse stiffener *a*⁶ also acts as the support of the brackets *f*² which carry the pivot shaft *f*¹ for the intermediate levers *f* (Figs. 1 and 2). It is advisable to provide three bearings, one in the centre and one at each side of the machine to prevent undue bending of the pivot. The pivot shaft *f*¹ may be prevented from swinging with the intermediate levers in any suitable manner, as for instance by means of clamping pins at the bearings *f*².

In order to facilitate the adjustment of the parts during assembly, all the intermediate levers *f* are provided with a hole *f*³ which holes all register when the levers are in their normal positions. Holes at suitable points are also provided in the side walls, so that a rod may be pushed through the holes when in line and the parts thus held with the levers *f* in their required positions whilst setting the draw bars *e* and *e*¹. The setting is such that the lever *f*, when swung forwards, does not pass to the front of the centre of shaft *f*¹ in plan. The connector *h* is coupled to the lever *f* at such a point that the said point swings with a slight downward path when operated. The depending arm of the

key lever, when in its extreme position in operation lies substantially underneath the pivot of the key lever *c*. Owing to this setting the type lever is moved with a uniformly 5 accelerated speed.

In order to give the type carrying ends of the type bars sufficient space on their supporting bed, in spite of the number of keys and the small size of the type bars, the bearing slots of the bars are pitched exceptionally 10 far apart and the angle taken up by the bars on the sector is also exceptionally large. In order that the angle of the outer draw bars shall not be excessive, the pivot shaft of 15 the intermediate levers is brought as close up to the rear row of keys as possible. This measure is rendered possible, as explained above, by the off-set eye on the connector *h*. As can be seen from Fig. 8, the off-set of the 20 connector *h* is in the opposite direction from the hook *e*³ and lever *c* and the roll of the eye is downwards as shown in order to prevent objectionable rubbing or friction between adjacent eyes. It has been found that 25 with any other arrangement, difficulties arise.

Fig. 4 shows how the long draw bars *e* are bellied in order to give sufficient space for the pin joint of the push bar of the rear row to 30 pass freely. The push bars *b* are not arranged centrally on the keys but to one side so to permit of the insertion of the back spacing and margin release keys in the keyboard.

35 The stepped bridge pieces *d* for the key lever pivots are provided at their ends with lugs *d*¹ and *d*² which are bent in opposite directions, the lug *d*¹ at the front being bent round whilst still remaining in a vertical 40 plane and the lug *d*² being bent upwardly in the plane of the bridge and then horizontally to be fixed to the underside of the transverse bar *a*⁵. The lug *d*¹ is turned in the direction opposite to the overhung bearing bush *c*³ of 45 the key lever *c* as this enables the back to front length of the machine to be reduced by the thickness of the bridge strip *d*¹.

The arrangement of the key lever pivot is shown in Fig. 9 and is designed with a 50 view to durability. The lever *c* bears on a bush *c*³ which is fixed by means of a threaded pin *c*⁴ having an enlarged head *c*⁴ to retain the lever on its bearing. The pin *c*⁵ is threaded into a tapped hole in the bridge 55 piece and a lock nut holds it in place as shown.

The space key shaft *a*¹¹ is supported between the rear rows of keys and the type rest *o* and is rotatable in its bearings in the 60 side walls of the machine. The space key arm *a*¹² which is fixed to the shaft *a*¹¹ is so shaped that it can move freely between adjacent bridge pieces *d*. The space key *m* is provided with an inlay of rubber, celluloid, 65 aluminum or the like. It has been found that

rubber makes the best inlay for the space key as it does not become soiled in use.

The type bars *g* are pivoted on a common wire *g*¹ passing through the slots *i*¹ of the sector *i*. The sector *i* is fixed to the cross bridge *a*⁷. The types are so fixed to the type bars *g* that they do not impinge on the roller at the level of the centre but a short distance above the centre, as shown in Fig. 1. This necessitates that the type should be set at 70 the correct angle so that when in printing position, the type face is inclined forwardly at its upper end. Reference has been made several times in this specification to the need for reduction of the height and length of the machine by detailed points of construction. The height of the machine is determined to a great extent by the length of the type bar, that is the distance from the centre of the type roller to the type bar pivot in the ordinary way of working with a vertical position of the type face in printing. The determining distance is thus the distance from the centre of the pivot of the bar to the 75 lowest letter. By the present invention, this usual determining distance is altered as the height from the base of the machine to the centre of the roller can be reduced by the distance between the centre of the roller and the centre of the lowest letter on the type bar. The work can be seen more readily as the printing is effected approximately in the line of vision of the operator. The type rest *o* must be given the same upward inclination 80 to correspond to the forward inclination of the type. 85

This rest is arranged at the sides in a curve corresponding to the radius of the type bar shaft *g*¹ but at the centre it is flattened. The inclined arrangement of the type rest face and the type together with the flattening of the rest strap *o* in the centre leave sufficient space between the base of the machine and the underside of the rest to admit the free operation of the swinging mechanism of the central type levers without necessitating the lowering of the bearing for the intermediate levers *h*. 90

Fig. 12 shows very clearly how the type bars at the side are spaced apart at a fairly 105 large angle. The connectors *h* are inclined at their rear edges as shown in order that they should not take up excessive space when swinging, more particularly in the 110 case of the outside type bars. By this arrangement the connectors never cross the vertical plane from the outer or rearmost point of the type bar to the base of the machine. 115

The carriage is movable backwards and forwards on ball or like bearings on the rear wall of the machine. The roller *n* is supported in swing levers for the purpose of raising and lowering it and these levers are pivoted 120 in the rear wall so that the line position will 125 130

be retained in both the cap and numeral register.

As there are three rows of type on each type carrier bar *g* and the printing face of these type is inclined to the horizontal plane through the centre of the roller *n*, see Fig. 1, the raising and lowering of the roller will not take place in a vertical plane but in one inclined at right angles to the radius shown 10 in dot and dash line form as passing through the face of the type carrier indicated in broken lines in the printing position.

It may be here stated that the most suitable material for the machine frame has 15 proved to be the metal known as duralumin, but other materials may be used if desired.

I claim:

1. A typewriter having in combination on a frame, a slidable carriage and roller in the 20 rear part of said frame, pivoted type levers adapted to swing upwardly to print on said roller, a keyboard with rows of keys and corresponding push rods at the front of said frame, two armed key levers operable by said 25 push rods and located beneath said keyboard, intermediate levers between each type lever and each key lever, draw bars arranged low in the machine and extending rearwardly from said key levers, connectors inclined upwardly and rearwardly from the rear end of 30 said drawbars to said intermediate levers and draw bars connecting said intermediate levers to the pivoted type levers.

2. A typewriter having in combination on a frame, a slidable carriage and roller mounted in the rear part of said frame, pivoted type levers adapted to swing upwardly to print on said roller, a key board with rows of keys and corresponding push rods at the front of 40 said frame, two armed key levers operable by said push rods and located beneath said keyboard, intermediate levers between said type and key levers, draw bars arranged in a horizontal plane at the bottom of said frame and 45 extending rearwardly from said key levers, connectors on the rear ends of said draw bars and extending upwardly and rearwardly to join said intermediate levers to said draw bars at a point above the pivot of said intermediate levers and drawbars connecting said intermediate levers to the pivoted type levers.

3. A typewriter having in combination on a frame, a slidable carriage and a roller mounted in the rear part of said frame, pivoted type levers adapted to swing upwardly to print on said roller, a keyboard with four rows of keys and corresponding push rods at the front of said frame, two armed key levers operable by said push rods and all pivoted individually in the same horizontal plane beneath said key-board, a transverse pivot shaft located near the base of the machine at a point about midway between the front and rear thereof, intermediate levers pivoted at their

lower ends on said transverse pivot shaft, draw bars arranged in a horizontal plane at the bottom of said frame and extending rearwardly from said key levers, connectors on the rear ends of said draw bars to an intermediate point in said intermediate levers and extending upwardly and rearwardly from said draw bar ends, draw bars extending rearwardly from the ends of said intermediate levers and connectors from said last mentioned drawbars to the type levers.

4. In a typewriter in combination with the pivoted type bars of key levers, a transverse shaft located at a midpoint between the front and rear of the machine, intermediate levers 70 pivoted on said shaft and having mutually registering holes therein at a point midway in their length enabling the said intermediate levers to be placed upon a common pin during the assembly in order to facilitate the adjustment of the parts, corresponding holes 80 in the adjacent parts of the side walls of the machine, threaded draw bars connecting the intermediate levers to the key levers and additional bars connecting the intermediate 85 levers to the type bars.

5. A typewriter having a frame with side walls, a keyboard with rows of keys therein, key-levers pivoted beneath said keyboard and operable by said keys, pivoted type bars in 95 said frame, intermediate levers between said pivoted key levers and type bars, said intermediate levers having holes therein which in the position of rest of said levers come into register with one another and with holes in the 100 side walls of the machine, and serve for taking up a common bar passed through the holes in order to lock the said intermediate levers, connecting means from the said key levers to said intermediate levers and separate connecting means from said intermediate levers to said type bars, both said means being adjustable as to length.

6. A typewriter having in combination with the carriage, roller, type carrying levers 110 and keyboard, two armed key levers all pivoted at the same level beneath said keyboard and having one arm operable by the keys in said keyboard, draw bars operable by the other arm of said key levers and extending rearwardly of the keyboard beneath the first mentioned arm of the key lever but to one side thereof and a laterally hooked end on said draw bar to engage the end of said key lever with said draw bar clear of the depressed key bar.

7. In a typewriter in combination with a nest of pivoted type levers arranged in a sector and adapted to swing upwardly to print, separately pivoted key levers at the 125 front of the typewriter, a transverse shaft arranged low in the machine at an intermediate point between the front and the rear, intermediate levers pivoted on said transverse shaft, drawbars offset from said key levers 130

- and extending rearwardly therefrom in a substantially horizontal plane at the bottom of the typewriter, upwardly and rearwardly extending connectors from said drawbars to 5 said intermediate levers, said connectors being offset sidewise from the drawbars in the opposite direction to the first mentioned offset and connectors from said intermediate levers to said type levers.
10. In a typewriter in combination with four rows of keys with push rods forming a keyboard at the front of the typewriter, four transverse rows of separately pivoted two armed levers located beneath said keyboard and each lever having a rearwardly extending arm connected to a key push rod and a depending arm and drawrods extending rearwardly from said depending arms, the drawrods from the front row of levers being 15 bellied where they pass beneath the operative connection of the rear row of levers with their push rods and the remainder of the drawrods passing rearwardly in parallel straight lines.
9. In combination with a row of pivoted type operating levers and transverse rows of keys spaced apart and all offset laterally in respect to one another, two fixed transverse bars parallel to one another, a plurality of stepped bridge pieces having steps corresponding to the rows of keys and fixed to said transverse bars to extend rearwardly and laterally beneath said keys with the steps of adjacent bridge pieces spaced at the spacing of the keys in the rows and the steps in each 30 bridge piece offset laterally in the same direction by the amount of the offset of the keys in parallel rows, separate pivots fixed to each step, two armed key levers mounted loosely in said pivots and having rearwardly extending arms to cooperate with the keys and also depending arms, and drawbars connected to said depending arms and extending rearwardly to said type operating levers.
10. In a typewriter in combination with a row of pivoted type operating levers, transverse rows of keys spaced apart and all offset laterally in respect to one another, two fixed transverse bars parallel to one another, the rear bar being at a higher level than the front 45 bar, a plurality of stepped bridge pieces having steps corresponding to the rows of keys, adjacent bridge pieces being spaced at the spacing of the keys in the rows and the steps in each bridge piece being offset laterally in the same direction by the amount of the offset of the keys in parallel rows, separate horizontal pivots fixed to each step of said bridge pieces, a holding lug at the front end of said bridge pieces and bent laterally in the 55 same direction as the steps are offset, a holding lug at the rear end of the bridge pieces and extending upwardly in the plane of the rear step and then laterally in a plane at right angles thereto and also to the plane of the first mentioned lug to connect to the rear 60 transverse bar at the higher level, two armed levers mounted loosely on said pivots and having rearwardly extending arms to co-operate with the keys and also depending arms and drawbars connected to said depending arms and extending rearwardly to said type operating levers.
11. A typewriter having a frame composed of side walls, a connecting back wall, a carriage and roller supported from said back wall, a transverse stiffening bridge fixed to the top of the side walls and having a segmental downwardly bent portion thereon, a segmental nest of type levers mounted pivotally on said segmental portion, a transverse stiffener at the bottom of said side walls and approximately midway between the front and rear thereof, a row of spring pressed intermediate levers supported on said bottom stiffener, a keyboard located between the front part of said side walls, two parallel spaced stiffeners joining said side walls at the front thereof, stepped bridge pieces extending between said parallel stiffeners and fixed thereto, key levers separately pivoted on the steps formed by said bridge pieces and individually operable from the superposed keyboard and connections from said key levers to said intermediate levers and from said intermediate levers to said type levers in the segmental nest.
12. In a typewriter having rows of keys all offset in respect to one another and forming a keyboard, stepped bridge pieces supported beneath said keyboard and transverse to the rows of keys thereof, bushes, threaded and headed pins holding said bushes and threaded into the steps of said bridge pieces, lock nuts locking said pins and two armed levers mounted loosely on said bushes and held in place by the heads on said pins, said levers being individually operable by the keys.
13. In a typewriter in combination with a carriage and roller, a segmentally arranged nest of type bars which strike upwards to print on the roller, means for reducing the overall height of the machine comprising a type face on the bar inclined forwardly in its printing position to print on the roller at a point above the horizontal plane through the centre of the roller, a type bar rest curved and inclined to suit the inclination of the type face, key operated levers at the front of the typewriter, a transverse pivot shaft supported low in the machine, intermediate levers mounted on said pivot shaft and operable beneath the said type bar, draw bars from said key levers to said intermediate levers and draw bars passing on the underside of said type bars to connect the intermediate levers to said type bars.
14. In a typewriter in combination with a carriage and roller, a segmentally arranged nest of type bars which strike upwards to

print on the roller, means for reducing the overall height of the machine comprising a type face on the bar inclined forwardly in its printing position to print on the roller at a point above the horizontal plane through the centre of the roller, a type bar rest curved and inclined to suit the inclination of the type face, key operated levers at the front of the typewriter, a transverse pivot shaft supported low in the machine, intermediate levers mounted on said pivot shaft and operable beneath said type bar rest, draw bars from said key levers to said intermediate levers, draw bars from said intermediate levers to said type bars and interposed connectors on said last mentioned draw bars and having their rear faces flattened and inclined outwardly and forwardly, substantially as described.

15. In a typewriter, a type action arranged to accelerate the type gradually on printing comprising, a pivoted type bar having a short driving arm inclined downwardly and rearwardly in the position of rest of said bar, an intermediate lever inclined rearwardly in its position of rest, a two armed key lever having a substantially horizontal and rearwardly extending key arm and a downwardly and rearwardly inclined arm, substantially horizontal connecting bars from said depending arm of the key lever to said intermediate lever, a link pivotally connected at one end

to the short arm of the type bar and a connecting rod connecting the other end of the said link with the rear end of the said intermediate lever. 35

16. In a typewriter, a plurality of operating keys arranged in rows, substantially vertically movable push rods supporting said keys, separately pivoted key levers having their pivots arranged forwardly in respect to the push rods, pins on the rearwardly extending arms of said key levers and with which said push rods engage and flat springs fixed to said key levers and engaging on the end 45 of said pins to hold said push rods thereon. 40

17. In a typewriter, a plurality of operating keys arranged in rows, substantially vertically movable push rods supporting said keys and tapered upwardly with a reducing 50 taper, transverse guide plates having slots to fit said tapered push rods when in their normal position, separately pivoted key levers having their pivots arranged forwardly in respect to the push rods, pins on the rearwardly extending arms of said levers and on which the said push rods engage and flat springs fixed on said key levers and engaging on the end of said pins to hold said push rods 55 thereon. 60

In testimony whereof I have signed my name to this specification.

ADOLF FRITZ SCHAUSS.
